UNITED STATES PATENT OFFICE.

JAMES W. REYNOLDS, OF CHICAGO, ILLINOIS.

DESIGN FOR ARTIFICIAL BAIT.

53,610.

Specification for Design.

Patented July 15, 1919.

Application filed March 3, 1919. Serial No. 280,477. Term of patent 7 years.

To all whom it may concern:

Be it known that I, JAMES W. REYNOLDS, a citizen of the United States, residing at Chicago, in the county of Cook and State of Illinois, have invented a new and original ornamental Design for Artificial Bait, of which the following is a specification, reference being had to the accompanying drawings, forming a part thereof.

Fig. 2 is a side elevation thereof.

I claim:

The ornamental design for artificial bait as shown.

In testimony whereof I affix my signature.

JAMES W. REYNOLDS.
